UNITED STATES PATENT OFFICE

HERMAN B. SMITH, OF PLAINFIELD, NEW JERSEY, ASSIGNOR TO THE BABCOCK & WILCOX COMPANY, OF BAYONNE, NEW JERSEY, A CORPORATION OF NEW JERSEY

DUST COLLECTOR

Application filed November 29, 1926. Serial No. 151,429.

This invention relates to an arrangement by which the waste heat from kilns such as cement kilns can be used, for example, to heat boilers for the generation of steam. The invention is especially useful in saving space and at the same time utilizing the heat in an effective manner, while also making the same flexible so that one or more of the kilns or one or more of the boilers may be cut off when desired.

10 The invention will be understood from the description in connection with the accompanying drawings in which Fig. 1 is a plan view; Fig. 2 is an end view partly in section and Fig. 3 is a vertical section along the line 3—3 of Fig. 1 or Fig. 2 the parts being shown somewhat diagrammatically.

15 In the drawings reference character 5 indicates a plurality of cement kilns of a well known type from each one of which waste gases are discharged into a compartment 6 in a housing. Each compartment 6 has a floor sloping at an angle slightly greater than the angle of repose of soot and dust so that 20 soot and dust will not accumulate on the floors of the compartments. Dampers 8 are provided on one side of the compartments and are movable vertically in guides so that 25 the compartments can be closed or opened at will by movement of the dampers 8. The compartments are provided with openings or 30 cleaning doors 9 near the upper edges of the floors to enable the floors to be cleaned if soot and dust should cling to the same. The compartments 6 all open into a lower common flue 35 10 that is horizontally disposed and is connected at one end by a passageway leading to the stack 12 with a damper 13 in the passageway.

40 Openings or passageways 14 are provided along the side of flue 10 and have transverse walls 14' extending along the bottom thereof. The dampers 15 vertically movable in guides are provided for closing the openings whenever desired.

45 Each one of the passageways or openings 14 leads to a boiler 16 and a suction fan 17 is provided for drawing waste gases through each boiler after which the gases pass into the 50 passageway 18 and then into the stack 19.

Hoppers 20 may be provided for collecting soot and dust after the gases pass over the heat abstracting surfaces of the boilers.

The operation is as follows: Hot gases from the kilns 5 pass into compartments 6 and thence downwardly into the flue 10, through the passageways 14, over the heat abstracting surfaces of the boilers 16, into the passageway 18 and thence into stack 19. When it is desired to shut off the boilers while the kilns 55 are still being operated the dampers 15 are closed and the damper 13 is opened, thus permitting the hot gases to pass into the stack 12 without heating the boilers. When it is desired to cut off only some of the boilers the 60 corresponding dampers 15 are closed and the damper 13 may be partially opened to permit a portion of the hot gases from the kilns to pass into the stack 12 while the remainder 65 heats the remaining boilers that are being 70 operated. When one or more of the kilns 5 are not being operated the corresponding damper or dampers 8 are closed, thus permitting the gases from the remaining kilns to pass into and away from flue 10, as heretofore described. The combinations are various and all conditions need not be specifically 75 described.

With the compartments 6, into which the kilns 5 discharge, arranged directly above the flue 10 less space is required for the installation. When the hot gases from the kilns discharge into the compartments 6 dust and soot therefrom settle in these comparatively quiescent spaces upon the floors 7 which slant 80 downwardly and from there the dust and soot pass into the flue 10 where they collect and can be removed from time to time. However, if dust and soot collect upon the floors 7 they 85 can be removed by rakes or the like passed through the openings 9. The partitions or walls 14' prevent a large portion of the dust and soot from being carried into the passageways 14.

I claim:

1. In combination, a plurality of kilns, separate compartments into which gases from said kilns are discharged, a common flue below said compartments connected to all of 100

said compartments and a damper between each compartment and said flue.

2. In combination, a plurality of kilns, separate compartments into which gases from said kilns are discharged, said compartments having sloping bottoms, and a flue to which said compartments are connected.

3. In combination, a plurality of kilns, separate compartments into which gases from said kilns are discharged, each of said compartments having a sloping bottom and an opening along one side near the upper edge of said bottom and a common flue into which said compartments discharge.

4. In combination, a plurality of kilns, separate compartments into which gases from said kilns are discharged, a common flue below said compartments connected to all of said compartments and a damper between each compartment and said flue, a stack to which one end of said flue is connected and a damper between said flue and stack.

5. In combination, a plurality of kilns, separate compartments into which gases from said kilns are discharged, a common flue below said compartments connected to all of said compartments and a damper between each compartment and said flue, discharge ports along the side of said flue and a damper in each port.

6. In combination, a plurality of kilns, separate compartments into which gases from said kilns are discharged, said compartments having sloping bottoms at an angle exceeding the angle of repose of soot and dust, and a flue to which said compartments are connected.

7. In combination, a kiln, a compartment into which said kiln discharges, said compartment having a sloping bottom and an opening through the wall thereof to give access to said sloping bottom.

HERMAN B. SMITH.
